UNITED STATES PATENT OFFICE.

NELS M. JOHNSON AND THOMAS S. QUIN, OF CHICAGO, ILLINOIS.

SAFETY-INDICATOR AND LICENSE-BRACKET.

1,291,010.

Specification of Letters Patent. Patented Jan. 14, 1919.

Application filed July 31, 1916. Serial No. 112,253.

To all whom it may concern:

Be it known that we, NELS M. JOHNSON and THOMAS S. QUIN, citizens of the United States, both residing at Chicago, in the county of Cook and State of Illinois, have jointly invented certain new and useful Improvements in Safety-Indicators and License-Brackets, of which the following is a specification.

10 This invention relates to an indicator for vehicles and has for its object the provision of a device adapted to normally serve as a tail light for the vehicle and which is readily controllable to indicate to persons in the rear of the vehicle the intended movements of the driver thereof.

15 A further object of our invention is the provision of means for electrically controlling a device of the character above described whereby the driver of the vehicle may indicate his intention with a minimum of effort.

20 A further object of our invention is the provision of means for utilizing the indicator to support and illuminate a license plate.

25 Further objects and advantages of our invention will be apparent as it is better understood by reference to the following specification when read in connection with the accompanying drawing, illustrating the preferred embodiments thereof, in which—

30 Figure 1 is a front elevation, partially in section, of an indicator according to our invention;

35 Fig. 2 is a section on the line 2—2 of Fig. 1;

40 Fig. 3 is a section on the line 3—3 of Fig. 1;

45 Fig. 4 is a diagrammatic view illustrating the electrical circuits.

50 Referring to Figs. 1 to 4 of the drawing, 1 indicates a casing which may be of any suitable construction and which preferably presents a semi-cylindrical front portion as illustrated in Figs. 2 and 3. An opening 2 is provided in the semi-cylindrical front portion which is covered by a glass 3 secured by suitable clips 4 to the casing.

55 The end 6 of the casing 1 is provided with a socket 7 to receive and support an

electric lamp 8 which projects into the casing 1 and is supplied with current through the conductors 9 from any suitable source. The end 6 is further provided with a bearing 10 to receive a trunnion 11 formed on a segmental end 12 to the periphery of which a semi-cylindrical member 13 is secured. 55

60 The opposite edge of the member 13 is secured to a segmental end 14 fastened to a shaft 15 which is journaled in a bearing 16 in the end 17 of the casing 1. The semi-cylindrical member 13 is thereby rotatably mounted in the casing 1.

65 The semi-cylindrical member 13 is provided with cut out symbols 18, 19, 20 and 21 spaced apart about its periphery, the symbol 18 being merely an elongated opening, the symbols 19 and 20 being left and right-hand arrows, respectively, and the symbol 21 being the word "Stop." The symbols are adapted to be selectively interposed between the lamp 8 and the opening 2 in the casing 1 and when so interposed an illuminated signal is displayed which indicates to persons in the rear of the vehicle 70 the intention of the driver thereof. 75

80 The means for rotating the member 13 to selectively display the symbols comprises a solenoid 22 supported on a suitable bracket 23 fastened to the interior of the casing 1 and a core 23 adapted to coöperate with the solenoid 22 and secured at one end to an arm 24 fastened to the shaft 15. A spring 25 surrounding the shaft 15 is secured at one 85 end to the end 17 of the casing 1 and at the other to the arm 24 and serves to retain the member 13 in position with the elongated opening 18 interposed between the lamp 8 and the opening 2 in the casing 1. 90 This is the ordinary tail light and with my device indicates that the driver intends to continue in motion or at rest as the case may be.

95 Secured to the end 17 of the casing 1 in spaced relation are a pair of solenoids 26 each provided with a core 27 which is normally held in the position indicated in Fig. 1 by a spring 28 surrounding the core. The inwardly directed ends of the cores 27 are 100 adapted when the solenoids 26 are energized to project into the path of the arm 24

and selectively limit the rotation of the arm 24 and consequently of the member 13 to interpose the left or right hand arrows 19 and 20 between the lamp 8 and the opening 5 2 in the casing 1.

To control the operation of the solenoids 22 and 26 a switch 29 is located preferably on or adjacent the steering column and is provided with a plurality of buttons 30, 31 10 and 32 adjacent which the symbols "Stop" and the right and left-hand arrows are marked on the switch 29. The buttons 30 and 32 are connected by conductors 33 and 34 to the solenoids 26 and 22 in series. From 15 the solenoid 22 a conductor 35 leads to a battery 36 or other source of current which is in turn connected by a conductor 37 to a bar 38 on the switch 29 with which the buttons 30 and 32 are adapted to contact to 20 close the respective circuits. The button 31 is connected by a conductor 39 to the solenoid 22 alone, whence the current passes through the previously described path to the bar 38.

25 From the foregoing description of the structure it will be apparent that when the button 31 is depressed current from the battery 36 will energize the solenoid 22 and the core 23 will consequently be drawn into the 30 solenoid to thereby rotate the member 13 until the symbol 21, indicating that the driver is about to stop, is interposed between the lamp and the opening 2 in the casing 1. If the driver intends to turn to the right the 35 button 30 is depressed and one of the solenoids 26 will be energized simultaneously with the energization of the solenoid 22. The core 27 will thereupon be projected into the path of the arm 24 and inasmuch as the 40 path of movement of the core is very much less than the necessary movement of the core 23 it will be apparent that the arm 24 will be arrested at the desired position with the symbol 20 interposed between the lamp 8 45 and the opening 2 in the casing 1. When the button 32 is depressed the operation will be similar, the other solenoid 26 being energized and the symbol 19 will be interposed between the lamp 8 and the opening 2 in the 50 casing 1.

The portion of the lamp 8 facing the opening 2 in the casing 1 may be suitably colored, for example the usual red, so that the signals will appear in this color. Brackets 55 40 are provided on the casing 1 adjacent the rear thereof to support a license plate 41 and an opening 42 in the bottom of the casing 1 permits illumination of the plate 41 by the lamp 8.

60 It will be readily appreciated that I have perfected a safety indicator and license bracket for vehicles which by reason of its simplicity of construction and ease of operation is extremely desirable and will prevent

many accidents, the common cause of which 65 is the failure of the driver to indicate his intention to persons and more particularly other drivers in the rear of his vehicle.

It will, moreover, be readily understood that various changes may be made in the 70 form, construction and arrangement of the parts without departing from the spirit and scope of the invention or sacrificing any of its material advantages, the forms hereinbefore described being merely preferred embodiments thereof.

We claim:

1. In an indicator for vehicles, the combination of a casing provided with a transparent portion, an electric lamp projecting into said casing from one end thereof, a member having a plurality of signals thereon and mounted to swing in said casing between the transparent portion thereof and the lamp, a shaft at the other end of the casing rigid 85 with said member, an arm on said shaft, a main solenoid having a core connected to said arm and adapted to be operated to rock said shaft, auxiliary solenoids having their cores arranged to project in the path of 90 movement of said arm, and means for energizing the main solenoid alone or in combination with one of said auxiliary solenoids.

2. In an indicator for vehicles, the combination of a casing provided with a transparent portion, an electric lamp projecting into said casing from one end thereof, a member having a plurality of signals thereon and mounted to swing in said casing between the transparent portion thereof and the lamp, a 95 shaft journaled in the other end of said casing and connected rigidly to the adjacent end of said member, an arm on said shaft, a main arcuate solenoid having an arcuate core connected to said arm and adapted to be 100 operated to rock said shaft, auxiliary solenoids arranged in an angular relation to the main solenoid with their cores arranged to project in the path of movement of said arm, and means for energizing the main solenoid 105 alone or in combination with one of said auxiliary solenoids.

3. In an indicator for vehicles, the combination of a casing provided with a transparent portion, an electric lamp mounted in 110 one end of said casing and projecting into the casing, a member having a plurality of signals thereon and mounted to swing in said casing between the transparent portion thereof and the lamp, a shaft journaled in 115 the other end of the casing and rigidly connected with the adjacent end of said member, a main arcuate solenoid arranged in the casing substantially below said shaft and between that end of the member to which the shaft is connected and that end of the casing in which the shaft is journaled and having an arcuate core, an arm rigid with the 120

shaft connected to the end of said core, a solenoid alone or in combination with one pair of auxiliary solenoids mounted in the upper portion of that end of the casing in which the shaft is journaled, spring pressed

cores in said auxiliary solenoids adapted to be projected in the path of movement of said arm, and means for energizing the main
